UNITED STATES PATENT OFFICE.

LOUIS WOJIDKOW, OF BROOKLYN, NEW YORK.

DESIGN FOR A KETTLE.

SPECIFICATION forming part of Design No. 25,481, dated May 12, 1896.

Application filed April 11, 1896. Serial No. 587,226. Term of patent 3½ years.

To all whom it may concern.

Be it known that I, LOUIS WOJIDKOW, a citizen of the United States, residing at Brooklyn, in the county of Kings and State of New York, 5 have invented and produced a new and original Design for Kettles, of which the following is a specification, reference being had to the accompanying drawings, in which—

Figure 1 is a perspective view, and Fig. 2 10 a sectional view thereof.

The leading feature of my design consists of a kettle-body having the peculiar outline as shown—that is, the lower portion of the body bulging outwardly and near its upper 15 end with an outwardly-flared and fluted flange and a restricted neck, the upper edge of which is also outwardly flared and fluted, said body being provided with a spout and fanciful handle.

A represents the body of the kettle, having 20 the peculiar shape shown and supported upon fanciful legs B. Near the upper end of the body is an outwardly-flaring and fluted flange C, the metal being returned upon itself and contracted into a neck D, the upper edge of 25 the latter being outwardly flared and fluted, as shown at E. To the body are secured the fanciful arms F, joined by means of the handle G. The body is provided with a spout H and a top or lid I. 30

What I claim is—

The design for a kettle substantially as herein shown and described.

LOUIS WOJIDKOW.
